BROKEN YARN DETECTOR

John L. Herman and Edwin Reidenbach, Fort Wayne, Ind., assignors of thirty-three and one-third per cent to John Archer, Fort Wayne, Ind.

Application December 28, 1937, Serial No. 182,116

4 Claims. (Cl. 66—163)

This invention relates to new and useful improvements in appliance for knitting machines and more particularly to a broken yarn detector.

The principal object of the present invention is to provide an appliance for knitting machines whereby detection of broken yarn will be accomplished at the instant it occurs.

Another important object of the invention is to provide an appliance which will detect and indicate the arrival of the end of yarn automatically.

Another important object of the invention is to provide an apparatus of the character stated which will efficiently take up slack yarn, replacing the ring and wire slides now in general use.

Another important object of the invention is to provide an appliance for knitting machines whereby the driving motor of the machine will be stopped instantly upon the occurrence of a break in the yarn.

These and various other important objects and advantages of the invention will become apparent to the reader of the following specification.

In the drawings:

Figure 1 represents a vertical sectional view through the appliance,

Figure 2 is a vertical sectional view at right angles to the sectional view shown in Figure 1,

Figure 3 is another sectional view showing the arm in lowered position,

Figure 4 is a sectional view taken substantially on line 4—4 of Figure 1,

Figure 5 is a sectional view taken substantially on line 5—5 of Figure 1,

Figure 6 is a fragmentary detail of the pivoted end of the feeler arm showing the insulated guide eye in section, and

Figure 7 is a diagrammatic view disclosing the electrical connections between the electrical devices involved.

Referring to the drawings wherein like numerals designate like parts, it can be seen that adjacent the yarn treating tank 5 is mounted a plurality of the appliances generally referred to by numeral 6. The yarn 7 passes through guide eyelets 8 in the wall of the treating tank 5.

Each of these appliances consists of a base structure 9 having ear portions 10 secured to the frame 11 of the machine by machine screws 12. The appliance consists of the case 13 having the removable side wall 14.

Secured to the back wall *a* of the case is the U-shaped member 15; this U-shaped member being provided with the ear 16 through which the member 17 extends and into the wall *a*. A short

shaft 18 extends through the leg portions of this U-shaped member 15 and passes through the loop 19 of the feeler arm 20, which arm is provided with the loop 21 at its free end through which the eye member 22 is disposed and through this eye member the yarn 7 travels as clearly shown in Figure 1. Springs 23—23 are provided on the pivot shaft 18 and are associated with the arm 20 in such a manner as to tend to urge the same downwardly to the position as shown by the lower dotted line in Fig. 1.

Adjacent the U-shaped member 15 is a second U-shaped structure 24 having the ear 25 connected as at 26 to the wall *a*. Through the leg portions of the U-shaped structure 24 is disposed the short shaft 27 which also passes through the ears 28 of the movable contact arm 29. Spring means 27—27' is provided on the shaft 27 and engaged with the ears of the movable contact arm 29 for normally tending to urge the curved end portion *b* of the movable contact arm against the stationary contact 30 on the arm 31. This arm 31 is suitably secured as at 32 to the wall *a*.

An arm 33 is also fixedly secured at one end to the wall *a*, the free end of the arm constituting the stationary contact 34 which terminates in spaced relation from the stationary contact 30, as shown in Figure 2 and adapted to be engaged and bridged by the end portion *b* of the movable contact arm 29.

A U-shaped member 35 is pivotally mounted on the shaft 18 and is provided with a tapered insulation block 36 engageable against the shoulder 37 on the movable contact arm 29. As shown in Figure 4, the block 36 is held by one end of the springs 23 in engagement with the movable contact arm 29 to oppose its circuit closing movement, but when the feeler arm 20 is moved into its lowered position, the block 36 responds to the spring pressure of the movable contact 29 to overcome the springs 23 so as to permit closing of the circuit, as shown by the dotted line position of the movable contact arm 29 in Figure 1.

It can now be seen that when the yarn 7 breaks, the feeler arm 20 will be moved downwardly by the springs 23, causing a decrease in the tension of the springs 23 on the block 36 and thus permitting the movement of the movable contact arm 29 toward the left to bridge the stationary contacts 30 and 34.

In this manner stationary contact 30 closes the circuit to the trouble light 41 and stationary contact 34 closes the circuit to the electro-magnet 39, the armature of which controls the conventional stop mechanism 40 of a knitting machine

motor (not shown), which is actuated by the armature of the electro-magnet when the latter is energized. Simultaneously the corresponding signal light 41 contained in the circuit 38 will become energized to indicate that the yarn is broken.

The feeler arm 20 acts as a take-up for slack yarn without releasing the movable contact arm 29, the range of movement for the slack take-up purposes being shown by the upper dotted line 10 position of the arm 20 in Fig. 1 and the lower full line position thereof. Movement of the arm 20 below said full line position will serve to release the arm 29 from its full line position as shown in Fig. 1 to the dotted line position at the left for bridging the contacts 30 and 34. The tension on the springs 23-23 during the lowering of the arm 20 decreases to the extent of permitting the springs 27'-27' to overcome the pressure of the first named springs and thus allow the closing movement of the arm 29.

While the foregoing specification sets forth the invention in specific terms, it is to be understood that numerous changes in the shape, size and materials may be resorted to without departing from the spirit scope of the invention as claimed hereinafter.

Having described the invention, what is claimed as new is:

1. In combination with a knitting machine, a 30 switch structure adapted for controlling the usual knitting machine stop mechanism and including stationary contacts and a movable contact, an arm pivoted at one end and having a yarn eyelet at the other end thereof and means yieldably connected to the arm adjacent its pivoted end and engaging the movable contact to normally maintain the latter out of contacting engagement with said stationary contacts.

2. A yarn controlled switch for knitting machines, comprising a pivoted arm having a yarn guide at its outer end, spring means engaging the arm for yieldably urging the arm in a direction for taking up slack in the yarn while the machine is in operation, a pair of stationary contacts having individual circuit connections, a

5 spring actuated movable contact adapted to bridge said stationary contacts to simultaneously close both circuits and means controlled by said arm for maintaining said movable contact out of engagement with the stationary contacts within a limited range of movement of said arm.

3. A yarn controlled switch for knitting machines, comprising a pivoted arm having a yarn guide at its outer end, spring means engaging the arm for yieldably urging the arm in a direction for taking up slack in the yarn while the machine is in operation, a pair of stationary contacts having individual circuit connections, a spring actuated movable contact adapted to bridge said stationary contacts to simultaneously close both circuits and means controlled by said arm for maintaining said movable contact out of engagement with the stationary contacts within a limited range of movement of said arm, said means comprising a pivoted member actuated by said spring means for engaging the movable contact member to oppose its circuit closing movement, said pivoted member responding to the spring pressure of the movable contact to overcome the first named spring means upon a predetermined movement of the arm.

4. In combination with a knitting machine, a switch structure adapted for controlling the usual knitting machine stop mechanism as well as a signal element, said switch consisting of a pair of stationary contact members adapted for controlling individual circuits leading respectively to the stop mechanism and to the signal element, and a spring actuated movable contact adapted to bridge said stationary contacts, an arm pivoted at one end and having a yarn eyelet at its outer end and means connected to the arm normally maintaining the movable contact out of engagement with said stationary contacts, said means releasing the movable contact for engaging the stationary contacts upon a predetermined decrease in the tension of the thread passing through the eyelet of the arm.

JOHN L. HERMAN.
EDWIN REIDENBACH.
